JABEZ CUREY NELSON, OF SYRACUSE, NEW YORK, ASSIGNOR TO EASY WASHING MACHINE CORPORATION, OF SYRACUSE, NEW YORK, A CORPORATION OF DELAWARE

EXTRACTOR BASKET FOR WASHING MACHINES

Application filed May 6, 1931. Serial No. 535,544.

This invention relates to a new and improved extractor basket for washing machines.

5 The invention relates to the type of extractor basket in which is provided an imperforate shell with a perforate lining in spaced relation to the side wall of the shell, and the main object of my invention is to provide a perforate lining of such construction that it may be easily and conveniently removed from the shell so that all parts of the basket may be quickly and easily cleaned.

10 Another object is to provide a lining for a basket of this character which will be retained in position without the use of any fastening means.

15 Other objects and advantages relate to the size, shape and arrangement of parts, all as will more fully appear from the following description taken in connection with the accompanying drawings in which:—

Figure 1 is a section on line 1—1 of Figure 2.

20 Figure 2 is a section on line 2—2 of Figure 1.

Figure 3 is a plan view of the lining for the basket.

25 My new and improved extractor basket may be used in combination with different types of washing machines either in a vat with a washing mechanism or in a separate vat, but for the purpose of explaining my invention, I have here shown the same in combination with a particular type of washing mechanism.

As here shown, a conventional frame 1 has secured thereon a vat 2.

30 A tube 3 extends upwardly into vat 2 and has secured thereto an agitator or dolly 4 for oscillatory motion. A shaft 3' extends upwardly through tube 3 and has secured to its upper end the extractor basket 5 for rotary motion therewith.

35 The extractor basket 5 comprises a circular upwardly and outwardly flaring imperforate side wall 6 which merges into an imperforate bottom 7.

40 At the point where the side wall merges into the bottom 7, there is provided an inter-

nal annular shoulder 8 for a purpose herein-after to be described.

The side wall 6 is provided with a plurality, in this case shown as six, of circumferentially spaced vertically extending ribs 9. 55

The ribs 9 are so formed that their inner edges extend vertically, and they are therefore spaced a gradually increasing distance from the side walls 6 as they extend upwardly. 60

An imperforate covering 10 having a central aperture is secured to the top edge of side wall 6.

Adjacent the upper edge of side wall 6 are provided a plurality of circumferentially spaced slots 11. 65

I provide an elongated perforated strip of an inherently resilient non-corrosive metal 12 such as copper. The strip 12 is somewhat longer than the greatest diameter of the side wall 6 of the outside container or shell formed by the side wall 6 and the bottom 7. 70

The width of the strip 12 is slightly less than the distance between the shoulder 8 and the cover 10. In order to assemble the strip 12 in the extractor basket 5 in order that the same may function as a perforated lining therefor, the strip 12 is rolled upon itself into approximately the form shown in dotted lines on Figure 2, and it is then passed downwardly through the aperture in cover 10 and is allowed to expand by its own inherent resiliency outwardly into contact with the ribs 9, and downwardly to rest upon the shoulder 8. The strip 12 being longer than the greatest inside circumference of the basket 5, it will slightly overlap, as shown at —a— on Figure 2, when it is in the operative position. 80

85 Although it is no part of the present invention, I have shown a means for disposing of liquid extracted from the clothes in the basket 5 comprising a cover 13 for the vat 2, which carries on its underside a circumferential trough 14. 90

95 Trough 14 has a discharge spout, not shown, so that liquid may be directed away from the vat 2.

The cover 13 is provided with cam members 15, one only being shown, which co-act with internally extending lugs 16 carried on 100

the wall of vat 2. The cover 13 is shown in the lowered position in heavy lines on Figure 1, but when the same is rotated, the cams 15 will ride upwardly on the lugs 16 and will 5 carry the cover 13 vertically into the position shown in dotted lines on Figure 1.

When the cover 13 is in the lowered position, the trough 14 will be beneath the openings 11 in the wall 6 so that water expelled 10 therefrom will flow into the trough 14 and around the same to and out of the discharge spout. The cover is left in this position when it is desired to dispose of the liquid expelled from the clothes extraneously of the vat 2.

15 When, however, it is desired to return suds, for example, to the vat 2 so that they may be re-used in washing a new batch of clothes, the cover 13 is moved to the raised position and when in this position, the trough 14 will be 20 above the openings 11, and the liquid expelled through such openings will return to the vat 2.

The side wall 6 of the extractor basket 5 flaring upwardly and outwardly, the liquid 25 which is extracted by centrifugal force from the clothes in the basket 5 will pass outwardly through the perforations in the lining 12, and will impinge against the side wall 6 and move upwardly to and out through the openings 30 11.

I have shown generally on Figure 1, as at 17, a portion of a means for oscillating the agitator 4, and for rotating the shaft 3, to cause rotation of the extractor basket 5, but 35 as will be appreciated by anyone skilled in the art, it will be possible to accomplish the desired result by any one of several well known mechanisms.

After the clothes have been washed and 40 dried, the operator may again roll the lining 12 upon itself to permit the same to be withdrawn from the basket 5 through the aperture in the cover 10, and this will permit the operator to conveniently and speedily clean 45 the interior of the shell formed by the side wall 6 and the bottom 7, and to also thoroughly clean the lining 12 before the same is returned to the basket 6.

I have provided no means for positively 50 locking the lining 12 in the basket 5 for I have found that the inherent resiliency of the strip 12 in conjunction with the centrifugal force exerted on it during the rotation of the basket 5 will cause the lining 12 to cling to 55 the ribs 9 and remain in fixed relation thereto.

I have here shown on Figure 2 a plurality, in this case shown as six, of radially extending vertical ribs 18 as a desirable means of 60 strengthening the bottom portion of basket 5.

Although I have shown a shell of a particular shape and a particular means for spacing the removable lining from the wall of 65 the shell, it will be understood that the shape

of the shell may be varied and that different means may be employed for spacing the lining from the wall of the shell, as may the height of the lining with respect to the shell without departing from the spirit of my invention, for although I have shown and described a specific structure and form and relation of parts as an exemplification of an embodiment of my invention, I do not desire to restrict myself to the exact size, shape or relation of parts as various changes may be made within the scope of the appended claims.

I claim:

1. An extractor basket for a washing machine comprising an imperforate shell having a bottom portion and an upwardly and outwardly flaring side wall, said side wall having an internal annular shoulder adjacent said bottom and a liner of resilient perforated metal resting on said shoulder and maintained in position by its own resiliency. 80

2. An extractor basket for a washing machine comprising an imperforate shell having a bottom portion and an upwardly and outwardly flaring side wall, said side wall having an internal annular shoulder adjacent said bottom and spacing ribs extending upwardly from said shoulder and a liner of resilient perforated metal resting on said shoulder and maintained in position against said ribs by its own resiliency. 90

In witness whereof I have hereunto set my hand this 30 day of April, 1931.

JABEZ CURRY NELSON. 100
